UNITED STATES PATENT OFFICE

EDWARD PARKER, OF NEW HAVEN, CONNECTICUT, ASSIGNOR TO THE
WINCHESTER REPEATING ARMS COMPANY, OF SAME PLACE.

MACHINE FOR GREASING CARTRIDGES.

SPECIFICATION forming part of Letters Patent No. 286,059, dated October 2, 1883.

Application filed August 6, 1883. (No model.)

To all whom it may concern:

Be it known that I, EDWARD PARKER, of New Haven, in the county of New Haven and State of Connecticut, have invented a new Improvement in Machines for Greasing Cartridges; and I do hereby declare the following, when taken in connection with accompanying drawings and the letters of reference marked thereon, to be a full, clear, and exact description of the same, and which said drawings constitute part of this specification, and represent, in—

Figure 1, a top or plan view; Fig. 2, a longitudinal section; Fig. 3, a transverse section; Fig. 4, a vertical section through one of the tubes, enlarged.

This invention relates to an improvement in the machine for greasing cartridges for which Letters Patent of the United States were granted to Henry S. Burns, September 12, 1882, No. 264,237. The invention of Burns had for its object to mechanically apply the grease to a number of cartridges hanging in a plate, and avoid the individual handling, as in previous methods. In the invention of Burns the cartridges are suspended by their head, the bullet downward, and over a bath of lubricating material in a heated state. A plate is immersed in the bath, which is perforated with holes corresponding substantially to the shape of but slightly larger than the body of the bullet. As the bullets hang over the bath, they are in axial line with the perforations in the plate which lies in the bath. Then the plate is raised from the bath up into the plane of the bullets, and so that the bullets enter the respective holes in the plate. The lubricating material adheres to the surface of the holes, and is transferred to the bullet by contact as the plate is thus presented. The thickness of the plate is less than the length of the exposed portion of the bullet, and so that the points will extend through the plates without contact, the intention of such extension of the bullets through the plate being to avoid greasing the extremity of the bullet; but in practice it is found that sometimes the holes will take up a greater quantity of grease than is necessary to deposit upon the bullet, or than the bullet will readily retain.

This is due at times to the formation of bubbles in the bottom of the holes, which serve to support a considerable quantity in the hole, and so that the entire surface of the bullet will be greased, and such quantity presented to the bullet is liable to run down upon the surface of the bullet and accumulate at the point. In either case the pointed portion of the bullet is greased, which it is desirable should be left clean.

The object of my invention is to avoid this liability of greasing the end of the bullet; and it consists in the arrangement of tubes of less diameter than the holes in the greasing-plate, and extending up through the said holes and so as to inclose the end of the bullet, the plate being permitted to work up and down over said tubes, as more fully hereinafter described.

The general construction is substantially the same as that in the Burns patent.

A represents the pan, in size corresponding to the work to be done, and in which a quantity of grease or lubricating material is held in a liquid condition by heat or otherwise, as indicated in Fig. 3. Within this pan a plate, B, is arranged in a horizontal plane, and so as to move freely up and down on vertical guides C. The mechanism for thus moving the plate hereshown consists of a rock-shaft, D, arranged longitudinally through the pan, with a lever, E, upon the outside, and provided with arms F, which extend into connection with the said plate, as seen in Figs. 2 and 3, whereby a rocking movement imparted to the shaft D will correspondingly raise the plate from or lower it into the pan, as indicated in Fig. 3. The plate B is perforated, as seen in Figs. 1 and 2, the shape of the perforations corresponding to that portion of the bullet upon which the grease is desired to be placed, but slightly larger in diameter.

H is a thin metal plate perforated corresponding to the perforations in the plate B, and arranged to be set upon the pan, as shown, and so that the perforations in the plate H will register or stand concentric with those in the plate below.

I is a plate arranged in a stationary position in the bath beneath the plate B, and upon this

plate vertical tubes *a* are arranged concentric with and corresponding to the holes in the plate B, but of less external diameter, and arranged so that the plate B may move freely up and down, while the tubes *a* remain stationary. The upper ends of these tubes, which stand concentric with the cartridge, receive the tip end of the bullet and extend onto the bullet to cover that portion of the point which it is not desired to grease, as seen enlarged in Fig. 4.

When the cartridges are arranged in the plates, the points of the bullets stand in their respective tubes *a*. Then the plate B is raised above the surface of the grease, taking upon the surface of the holes the grease to deposit upon the bullet, as in the Burns machine; but because of the tubes *a*, which stand within the holes, there is no possibility of the formation of bubbles, or of taking up any more grease than can lie in the holes around the tube. The grease thus taken is deposited upon the bullet, and then the plate B returned. The tubes *a* protect the end of the bullet and prevent the possible depositing of grease thereon, or its running down upon the bullet as the plate descends, as it is liable to do in the Burns machine. The grease will chill sufficiently upon the bullet before it can be removed, so that there is no liability of its flowing below the point indicated by the upper end of the tubes.

Another advantage of this arrangement of

tubes is that the cartridges are brought into an exact perpendicular position—that is, axial line with the tubes—thus insuring an equal deposit upon all sides and preventing the possibility of the cartridges getting out of such proper axial line. I employ tubes to thus cover the end of the bullet; but I wish it to be understood that by the term "tube" I intend to embrace any cover for the end of the bullet standing in an axial line with the cartridge and with the holes in the greaser-plate.

I claim—

The combination of a pan constructed to contain the lubricating material in a liquid state, a plate arranged in said pan in a horizontal plane upon guides, and so as to be immersed in or raised from the lubricating material, the said plate perforated corresponding to the portion of the cartridge to be lubricated, a plate arranged over said movable plate, correspondingly perforated, through the perforations of which the cartridges to be lubricated may be suspended above the lubricating material, and tubes *a*, concentric with the cartridges, and so as to cover the point of the bullet before the lubricating material is presented, substantially as described.

EDWARD PARKER.
